Application February 3, 1947, Serial No. 726,090

26 Claims. (Cl. 123—127)

1

This invention relates to engines and more particularly to a system for and the method of supplying fuel to engines.

This application is a continuation in part of my application Serial No. 429,683 filed February 5, 1942, now abandoned. Modern carburetors are usually provided with means for controlling the richness of the fuel mixture in accordance with any one of at least three separate and distinct flow curves. These curves are known to those skilled in the art as the part throttle curve, the wide open throttle curve, and the starting mixture curve. It has also been recognized as necessary to provide means for a substantial reduction of the fuel content of the mixture under conditions when the operator, in trying to start the engine, has flooded it with fuel to such a point that the engine will not fire. The fuel supplied to meet this condition is known as the unloading curve. It will be understood that the wide open throttle curve represents the mixture necessary for maximum power, that the part throttle curve represents the mixture for maximum economy in which the fuel content is less than that for maximum power, the starting curve represents the fuel mixture delivered under cranking conditions with the choke valve closed, and the unloading curve represents cranking conditions with wide open throttle and open choke.

I have found that the compression ratios of engines can be successfully increased, or lower octane fuel can be used, or both, by increasing the richness of the fuel mixture beyond that supplied for maximum power. It is, therefore, an object of the invention to provide means for adding a fifth condition or curve which represents a mixture richer than that required for maximum power which is proportioned for and delivered automatically when anti-detonating conditions are encountered.

Such excessively rich mixtures as are not required for this purpose would be uneconomical if used when not needed, and in order to enable the operator to make efficient use of my invention, it is important that he be informed of the operating condition of the carburetor at all times and to know what kind of a fuel mixture it is delivering. There are several reasons why it is important to furnish this information; for instance, the operator would soon discharge his battery if he tried to start the engine by cranking it while the unloading mixture is being delivered.

Another object of the invention is to feed fuel to an engine in such a manner as to eliminate detonation and increase compression ratio.

A further object of the invention is to supply anti-detonant fluid to an engine fuel feeding system controlled by engine developed suction values.

Another object of the invention is to prevent

2

engine detonation by increasing fuel content of a carbureted mixture, when required, beyond that supplied for maximum power, usually when the engine is operating below a predetermined speed value.

Figure 1 is a sectional view of an internal combustion engine to which the invention is applied.

Figure 2 is a diagram of the device incorporating the invention.

Figure 3 is a diagram of the flow curves supplied to the engine.

Figure 4 is a diagram of another form of the invention.

Figure 5 is an elevational view of the device shown in Figure 4.

Figure 6 is another elevational view of the device shown in Figure 4.

Figure 7 is a sectional view of the signal switch device.

The following elements, cylinders 34, piston 218, connecting rod 219, wrist pin 220, crankshaft 221, cam shaft 222, spark plugs 223, head 224, intake valve 225 and cam follower 226 shown in Figure 1, are parts of a conventional internal combustion engine.

Referring to Figures 2 and 3 of the drawings, the reference numeral 1 indicates the mixing conduit or barrel of a carburetion system leading into the cylinders of an internal combustion engine. The reference numeral 2 indicates an unbalanced choke valve which is controlled by heat and suction and embodies a construction generally in accordance with Patent No. 2,085,351. The throttle valve 3 is connected to a starter control switch 4 which may be made in accordance with the starter control switches shown in Patent No. 2,174,313, Patent No. 2,053,094, or Patent No. 2,147,019.

The carburetor has the usual Venturi stack 5 and the main fuel nozzle 6, which is supplied with fuel from a float bowl 7 or other source, that discharges into the venturi. An anti-detonating fluid nozzle 8 fed from a float controlled reservoir 9 also discharges into the venturi. An idling fuel passage 10 discharges adjacent the edge of the throttle valve 3 when in closed position. The starter motor contact is indicated at 11, and this contact is operated by a partial opening movement of the throttle valve. A second contact 12 is arranged to be contacted by the switch member 4 at a point in the opening movement of the throttle substantially later in the opening movement of the throttle than contact with the terminal 11. This second contact controls the signal circuit. The switch operating rod 230 is connected to the live lead 231 from the battery or other current source 232, and the switch member 4 at the end of the switch operating rod first slides under the contact 11 to complete the starting motor circuit and upon further opening

movement of the throttle makes contact with the terminal 12, the starter contact 4 then being out of contact with contact 11.

A carburetor metering rod 13, provided with several steps of different diameter, controls the admission of fuel to the main nozzle 6. The metering rod is connected by means of linkage to the throttle valve 3. This linkage comprises an arm 15 rigidly connected to the throttle shaft 17, lost motion and spring devices 115 and 116, a weak spring 117, lever 118 pivoted to the carburetor body at 119, link 154, and rocker arm 14 which is mounted on a fixed pivot 141. The spring 120 normally acts on the rocker arm to hold the metering rod in the leanest position, and the weak spring 117 only partially overcomes the spring 120 as the throttle is moved to nearly wide open position. This action brings the step 133 of the rod 13 into operation in the orifice 132 for providing greatest power in the economy range, but does not bring the step 134 of the metering rod into action for providing maximum power beyond the economy range. When the throttle is finally moved to its fully open position, the lost motion in the member 115 is taken up, and the spring 116, acting in conjunction with spring 117, overcomes the spring 120 sufficiently to bring the smallest step 134 of the metering rod into action to provide maximum power.

A volume control and vaporizing valve 16 is mounted in an unbalanced relation, posterior to the throttle valve, on shaft 17 and is normally held in closed position by a spring 18. This valve is capable of being opened mechanically by throttle actuated mechanism, by the direct action of suction in the manifold or by suction operation of piston 19, it being noted that piston 19 is connected to the valve shaft 17 by means of a loose lever 27 engaging a one-way stop 28 on shaft 17.

The piston 19 is mounted in a cylinder 29 which is connected by means of a passageway 21 to the intake manifold posterior to the volume control valve. The valve 16 is also provided with a lost motion, one-way connection 22, whereby it may be held in at least partially open position by holding the throttle valve in wide open position. However, the spring 180 behind the switch contact 11 has such substantial strength, that if the operator attempts to move the throttle valve beyond the normal starting position in which the switch member 4 makes contact with the member 11, at which point the lost motion in member 22 is taken up, he meets a substantial resistance to further opening.

This resistance serves as a signal to the operator that he is moving the throttle valve beyond the proper starting position. The resistance of spring 180, however, disappears when the motor starts.

In case the operator desires to unload the engine so as to relieve a flooded condition, he opens the throttle against the resistance of the spring 180, thereby opening the choke valve 2 by means of the one-way connection 23, which opens the choke valve against the resistance of the thermostat 24 which normally holds the choke valve in closed position for the cold starting operation. This movement of the throttle valve to the unloading position also causes the switch member 4 to contact the member 12 which is connected to a signal light 25 to indicate to the operator that the carburetor is in the unloading position.

A feature of this invention is that the small step

134 at the lower end of the metering rod comes into operation at the same point at which the switch 4 contacts the switch 17 so that the signal light 25 serves not only to indicate the unloading condition during the cranking period, but also serves to indicate the completely open throttle for providing enrichment for either maximum power or anti-detonation depending upon the engine speed.

10 The throttle position for maximum power in the economy range is within 10 or 15 degrees of fully open position, during which condition metering pin step 133 is effective. When the throttle is in this position, it presents no substantial resistance 15 to flow of the fuel mixture to the engine, even at fairly high speeds, but if the operator wishes to get the absolute maximum of power beyond the economy range, he will naturally press the accelerator to the floor and tend to force the throttle to its fully open position and will move pin 13 to make step 134 effective. At this point, the lost motion link 22 operates the lever 26 and forcibly opens the valve 16.

15 It will be noted that the rocker arm 27 is rotatably mounted on the shaft 17, but as shaft 17 is provided with projection 28 in the path of movement of the rocker arm 27, piston 19 can be actuated to pull the valve 16 to open position, but the valve 16 cannot operate the rocker arm 27. 20 Connected to the rocker arm 27 is a valve 29 controlling an air vent opening 30 which has sufficient capacity to kill the suction in the nozzle 6.

25 When the suction piston 19 is not operated by the suction, the spring 31 at the end of the cylinder behind the piston moves it to the left and keeps the valve 29 closed so that the nozzle 6 can be operated by suction to supply anti-detonating fluid to the venturi. This anti-detonating fluid may be water alone, or water mixed with an 30 anti-detonating fluid or fuel, such as tetra ethyl lead or alcohol. Also, the fluid may be merely additional gasoline, in which case, the supply chamber 9 may be identical with the chamber 7.

35 Referring to Figure 3, this is a diagram showing the approximate fuel mixture flow curves in which the part throttle or economy power range curve is indicated by A—A; B—B is the maximum power curve; C—C is the starting mixture curve; D—D is the unloading curve, and E—E is the anti-detonating curve. The vertical line represents 40 ounces of fuel per 100 feet of air flow through the carburetor and the horizontal line represents 45 cubic feet of air per minute passing through the carburetor.

50 Below the valve 16, the discharge outlet is yieldably closed by an unbalanced valve 15 mounted on the shaft 16 and normally lightly held in closed position by the weight 11. The passageway 1, which may be termed the mixing conduit, is provided with a by-pass 18 which leads to a hot spot 19 heated by the exhaust manifold 80 of the engine. This by-pass is normally closed by the butterfly valve 81 mounted on shaft 82 and connected by link 83 to the piston 19. By this arrangement, the mixture must flow to the engine 55 through the mixing conduit 1, which is heated only slightly, if at all, as long as there is no suction in the discharge outlet. When there is suction applied to the piston 19 sufficient to open the valve 16 beyond the point at which the lost motion 60 in the broken link 83 is taken up, valve 81 is opened so that the fuel mixture is directed through the by-pass hot spot.

65 This arrangement is a reversal of previous ideas, as it has been customary to put the hot

spot by-pass in the exhaust passage, whereas, I put the by-pass in the intake or mixing conduit. There are several reasons for this, but one of the important reasons is that when the operator suddenly opens the throttle, as when he desires to suddenly accelerate the engine, he immediately has available a supply of cold mixture which does not detonate as easily as hot mixture. With the previous construction, it took several seconds to obtain any substantial reduction of hot spot temperature, so that the detonation occurred regardless of the fact that the heat might have been turned off from the hot spot.

The valve 75 is controlled by a heat responsive device, such as a bimetallic coiled spring thermostat, which may be supplied with heat from the hot spot conducted through the surrounding metal or by any other desirable means, such as enclosing it in a housing and sucking heat from a stove through the housing as shown in said Patent No. 2,085,351. It will be noted that the valve 81 is unbalanced and suction responsive and may also be controlled by a thermostat, if desired, but I prefer to control only the valve 75 by thermostatic means, as the main mixing conduit in which the valve 75 is mounted is not subject to much heat and, therefore, not subject to warpage and distortion which would result in sticking of the valve shaft as so frequently happens when the valve is mounted in the exhaust conduit, as in previous practice. It should also be noted that the thermostat does not forcibly open the valve 75 but merely releases the closing tension on it to such a point that the pressure is no longer sufficient to overcome the light spring 86 which holds the valve 81 lightly in closed position.

Figures 4 to 7 inclusive show another form of the invention and in the description thereof numerals similar to those previously employed will be used where possible. The delivery end of the mixing conduit 1 is shown connected with riser 32 of the fuel intake manifold 33 that is open to the cylinders 34 of the engine. The metering pin 13 has three reduced diameter steps 133, 134 and 135 adapted to cooperate with orifice 132. Suction passageway 21 connects cylinder 20 with a vertical passage 21' in the wall of the carburetor of the barrel which opens into the smallest venturi in the stack 5. Reservoir 9 for the anti-detonant fluid feeding system is formed integral with barrel 1 and a passage 36 connects the reservoir 9 with nozzle 8, a constant level of fluid being maintained in reservoir 9 by means of float 35. Air bleed passage 30 opens into passage 36 above the fuel level and is controlled by valve 29 fixed to control rod 37. It will be noted that the cylinder 20 is open to suction in the venturi in this form of the invention instead of to suction in the delivery conduit posterior of the volume valve 16 as in Figure 1.

The control for fuel flowing to main nozzle 6 is partly similar to that shown in my co-pending application, Serial No. 591,126, filed April 30, 1945, now Patent No. 2,477,481, issued July 26, 1949. Formed in the wall of the mixing conduit 1 is a cylinder or chamber 38 communicating through a passage 39 with opening 40 in the mixing conduit posterior of the throttle valve. Slidable within chamber 38 is a piston 41 having an elongated rod 42 projecting thereabove through cover 43 of the fuel bowl and having at its upper portion a laterally offset arm 44 pinned as at 45 to the metering rod 13.

A spring 46 in the suction chamber 38 constantly urges piston 41 upwardly and may be

calibrated to move the smallest portion 135 of the metering pin into operative relation with orifice 132 to provide an extra rich mixture when the suction posterior to the throttle valve drops below a predetermined value, say three inches of mercury. At other times, the metering pin will be drawn down by suction so as to bring a larger portion thereof into the metering orifice to provide an economical mixture for part throttle operation or for maximum power as dictated by the throttle valve position.

Rocker arm 47 is pivotally mounted on stanchion 48 above the fuel bowl cover and is moved in a definite relation with the throttle valve by arm 49, link 50 and arm 51 fixed on the throttle shaft 157. A lip 52 extending from the rocker arm 47 is so positioned as to extend under a laterally offset lip 53 formed on the upper portion of the elongated piston rod 42 for limiting the downward movement of metering rod 13 in accordance with a predetermined positioning of throttle valve 3 to provide desired fuel mixture.

The carburetor body is also formed with a chamber 60 for receiving piston 63 and spring 66. Passage 61 communicates at one end with the lower end of chamber 60 and has the other end 62 opening into the venturi 5. Rod 64, extending through the cover 43, is pinned at 60 to piston 63 and terminates in a turned over outer end 65 forming a finger for restricting upward movement of the metering pin when vacuum values in the venturi act on piston 63 to overcome the pressure of spring 66.

Piston 19, valve 81 and vent valve 29 are connected with volume control valve 16 by linkage. Rocker plate 67 is loosely mounted on one end of volume valve shaft 17 and has a lost motion link 68 connecting it with pin 69 fixed on arm 82 fixed on the shaft for valve 81. Rod 70 on piston 19 is connected by link 71 with rocker plate 67 and vent valve rod 37 is connected with piston rod 70 by link 72.

The volume valve 16 is normally urged toward closed position by spring 73 fixed at one end to pin 74 on conduit 1 and at the other end to pin 87 fixed on arm 88, such arm being fixed on the end of shaft 17 opposite from arm 67. The throttle valve shaft 157 is operated by arm 89 and link 90 connected to the arm and extending to the usual vehicle driven instrumentality, such as the accelerator pedal (not shown). Arm 89 has a segmental opening 91 through which pin 87 projects and shoulder or abutment 92 is engageable with the pin 87 to positively open the volume valve when the throttle valve is moved to its full open position.

The choke valve also may be opened for unloading through operation of arm 89. Link 93 is pivoted at 94 to arm 89 and has a cam head 95 adapted to actuate arm 96 fixed on one end of the choke valve shaft 97. Rod 93 has a guide slot 98 through which pin 99 fixed on conduit 1 projects.

The signal light 25 is connected with terminal 100 of a micro-switch 105 by a lead 101 and switch terminal 102 is connected by a lead 103 to battery 104. The switch has an operating plunger 108 in position to be engaged and depressed by a nose 109 on throttle shaft arm 51 to close the switch points during the unloading operation and thereby energize signal light 25.

The starter switch 4 (Fig. 7) is also controlled by the throttle valve shaft 157 in the manner shown in Patent No. Reissue 22,385 issued October 26, 1943, to Irven E. Coffey. The shaft has

a dished portion 214 receiving a ball 110 for advancing a plunger 107 upon opening of the throttle to close the switch. Ball 110 may be lifted by engine suction when the throttle is closed so that thereafter operation of the throttle does not affect the starter switch.

The metering pin 13 has three tapered steps 133, 134 and 135 of reduced diameters, thus providing four diameters adapted to cooperate with orifice 132 for varying the amount of fuel supplied from nozzle 6 to the conduit 1.

When step 133 of the metering pin is effective, the fuel supplied from the carburetor bowl is proportioned to provide a relatively lean mixture for maximum economy. When the throttle valve is substantially opened to make step 134 on the metering pin effective to supply a power mixture, shoulder 92 on arm 89 will engage pin 87 and positively shift volume valve 16 to open position, otherwise such valve opens in accordance with suction in the intake manifold. Valve 16 will thus also be mechanically opened when the choke valve is opened for the unloading operation.

As rocker plate 67 is rotatably mounted on volume valve shaft 17 actuation thereof by piston 19 will shift link 68 to forcibly open valve 81 when the suction in conduit 1 is strong, such mechanism corresponding to linkage 83 in Figure 2. Shaft 17 also carries a pin 301 which engages an outwardly projecting lug 302 on plate 67 to forcefully close the volume valve when suction in venturi 5 is weak. Plate 67 can rotate the shaft 17 through this connection but shaft 17 cannot rotate the plate, such mechanism corresponding to the one-way connection between lug 28 and rocker 27 in Figure 2.

When the engine is cold and inoperative, thermostat 24 holds the choke valve 2 substantially closed and as there is no vacuum in conduit 1 spring 66 will place stop finger 65 in its uppermost position so that spring 46 can hold the metering pin in its uppermost position placing step 135 in orifice 132 to allow maximum fuel delivery from jet 6. At the same time, as there is insufficient vacuum to displace the bleed valve 29, the anti-detonant fluid system is closed.

In starting an engine equipped with the mechanism shown in Figs. 4 to 7, the throttle valve is partly opened to make the electric starter system switch 4 effective and thereby cranking the engine so that sufficient suction is created to draw fuel into the conduit from nozzles 6 and 8. This mixture will be extremely rich as fuel is metered by step 135 and from the anti-detonant system. The curve for starting will be much higher for the mechanism in Figs. 4 to 7 than curve C—C of Fig. 3 shown for the Fig. 2 mechanism, as cranking suction in the latter form will not be sufficient to withdraw anti-detonant and step 133 will be effective so maximum fuel is not drawn from nozzle 6. Cranking suction will open volume valve 16 slightly but the suction is not sufficient to overrule spring 31 enough to open the bleed valve 29 which will thus remain closed. Liquid from bowl 9 will be drawn from the bowl through nozzle 8, fuel from bowl 7 will be drawn through nozzle 6 and some fuel will be drawn from the idling passage 10 having its inlet 10' in the main nozzle passage. The starting charges have a high fuel content so that quick starting will result even though valve 81 has closed the heated by-pass 79.

In case the engine stalls from an overabundance of liquid fuel while starting, the throttle valve is fully opened. Link 93 is pushed up by

this positioning of the throttle valve and cam head 95 will rock arm 96 to partially open choke valve 2 in case it is closed by the thermostat. The air flow is thus much increased and will unload the rich fuel charges as cranking is continued, the throttle being returned to starting position when the unloading has been completed. During this unloading operation, the signal switch 105 will be closed to energize the signal circuit. The operator will thus be advised that unloading is in progress so he will not thus run down the battery, the starter circuit being maintained while unloading. Full opening of the throttle valve also will cause abutment 92 on arm 89 to carry pin 87 to a position fully opening volume valve 16 whereby unloading flow will be unrestricted. Suction at such time is insufficient to draw liquid from either of the nozzles 6 and 8. The flow curve for this operation is shown by line D—D in Figure 3.

Assuming now that the engine has started, the throttle valve is allowed to return to idling position, as shown in Figure 4, thus releasing ball 110 and breaking the starter circuit. The throttle valve is almost closed and vacuum in passage 39 will overrule spring 46 to move piston 41 and member 42, to shift metering pin 13 so that its largest diameter is in orifice 132. The starter switch and signal switch will be open and volume valve 16 is free to be opened by suction against spring 31 which suction will also act on piston 19 to overrule spring 31 thereby opening bleed valve 29 cutting off the anti-detonant fuel supply that was effective while starting. Fuel will be drawn through idling passage 10 and port 10'.

Upon partial-opening of the throttle valve the engine will operate in the economy range. In this range the metering pin will be shifted upwardly by the throttle valve shaft, by means of arm 51, link 50, rocker 47, lip 52 and lip 53, to place intermediate, step 133 or the upper portion of step 134 in orifice 132. Obviously the smaller the pin diameter in the orifice the greater will be the volume of fuel flow to air. Suction will move piston 19 to open valve 29 and will overrule spring 46 sufficiently to hold pin lip 42 against lip 52. The volume valve will be opened in accordance with engine developed air flow in the manifold and unless there is a suction reduction, spring 31 will be overruled and valve 29 will be open making the anti-detonant liquid feeding system ineffective. It will be understood that maximum power is not developed by this control but that maximum economy is attained. The flow curve for this operation is indicated by line A—A in Figure 3.

Assuming that the engine is operating above a predetermined speed and that the throttle valve has been moved to wide open position, the lower portion of step 134 lies in orifice 132 and the fuel mixture will be enriched to develop maximum power beyond that possible in the economy range. Suction overrules spring 66 to place stop finger 65 in the path of the metering pin to prevent spring 46 moving step 135 into orifice 132. Abutment 92 will carry pin 87 to fully open volume valve 16. The anti-detonant fluid system will be ineffective because vacuum will overrule spring 31 so as to open the bleed valve 29. The fuel delivered through nozzle 6 will be in excess of that delivered in the economy range, consequently maximum power will be developed. The signal circuit will be closed. The flow curve for this maximum

power development is indicated by line B—B in Figure 3.

Detonation is prevented when the throttle valve is wide open or in maximum power position and the engine is operating below the predetermined value in its speed range. Vacuum in venturi 5 is low so that spring 66 moves stop finger 65 upwardly out of the path of the metering pin and spring 46 is effective to lift the metering pin to place step 135 in orifice 132. Thus there is an increase of fuel fed from bowl 7 through nozzle 6 beyond that fed for maximum power. Vacuum will be too weak to overrule spring 31 which will hold piston 19, rod 10, link 12 and rod 37 to close bleed valve 29 whereby causing feeding of anti-detonating fluid from bowl 9. At the same time, in wide open throttle valve position, abutment 92 will shift pin 87 to fully open the volume valve 16 and the signal circuit will be closed. The anti-detonant fuel and the enriched carbureted mixture will both be effective to prevent detonation. The flow curve for this condition of operation is indicated by line E—E in Figure 3. As soon as the engine speed increases beyond the predetermined value, vacuum will return the metering pin to maximum power position, will move stop 65 to prevent step 135 becoming effective and will open bleed valve 29 making the anti-detonant system ineffective. The signal system is still effective.

It will be understood that valves 75 and 81 and their control operate the same as set forth in the description of Figure 2.

The exclusive use of all modifications as come within the scope of the appended claims is contemplated.

What I claim is:

1. In an internal combustion engine having an intake conduit and an exhaust passage, a valve mounted in said intake conduit and a by-pass leading around said valve, said by-pass having a portion heated by said exhaust conduit, said by-pass having a valve therein and heat responsive means for controlling at least one of said valves.

2. In an internal combustion engine, a fuel supply device having means for selectively supplying fuel mixture in accordance with the requirements for maximum economy and a different mixture in accordance with requirements for maximum anti-detonating effect, means for heating the mixture delivered by said device, and means for reducing the heating effect of said heating means when the device is operated to supply the anti-detonating mixture.

3. In a fuel supply device for internal combustion engines, means forming a mixing conduit, a fuel supply means discharging into said mixing conduit, valve means for controlling the volume of fuel mixture supplied through said conduit, means for controlling the richness of the mixture in accordance with the requirement for maximum economy during part throttle operation, means for enriching the fuel mixture in accordance with the requirements for maximum power when the valve is moved to nearly wide open position, heating means for maintaining the fuel mixture at a temperature for producing maximum economy and power conditions, and means for further enriching the mixture in accordance with the requirements for maximum anti-detonating effect when the valve is moved to fully open position, said heating means being regulated to maintain the en-

riched anti-detonating mixture at such a temperature as to secure a maximum anti-detonating effect.

4. In a fuel supply device for internal combustion engines, means forming a mixing conduit, a fuel supply means discharging into said mixing conduit, valve means for controlling the volume of fuel mixture supplied through said conduit, means for controlling the richness of the mixture in accordance with the requirement for maximum economy during part throttle operation, means for enriching the fuel mixture in accordance with the requirements for maximum power when the valve is moved to nearly wide open position, means for further enriching the mixture in accordance with the requirements for maximum anti-detonating effect when the valve is moved to fully open position, temperature varying means being so constructed and arranged as to insure maximum economy at part throttle conditions, maximum power at open throttle conditions, and maximum anti-detonating qualities upon enrichment of the fuel mixture for anti-detonating purposes.

5. In a fuel supply device for internal combustion engines, means forming a mixing conduit, a fuel supply means discharging into said mixing conduit, valve means for controlling the volume of fuel mixture supplied through said conduit, means for controlling the richness of the mixture in accordance with the requirement for maximum economy during part throttle operation, means for enriching the fuel mixture in accordance with the requirements for maximum power when the valve is moved to nearly wide open position, means for further enriching the mixture in accordance with the requirements for maximum anti-detonating effect when the valve is moved to fully open position, heating means for said fuel supply, and means for subjecting such portions of said fuel supply to said heating means as to maintain the temperature of the entire supply at a degree producing maximum effectiveness throughout the engine operation.

6. In a fuel supply device for internal combustion engines, means forming a mixing conduit, a fuel discharge means discharging into said conduit, valve means for controlling the volume of fuel mixture supplied through said conduit, means for enriching the fuel mixture in accordance with the requirements for maximum anti-detonating effect when the valve is moved to fully open position, heating means for maintaining the fuel supply at temperatures for producing maximum power and economy, and means for minimizing the temperature of the fuel supply for anti-detonating purposes to a point comparative to best anti-detonating qualities of the mixture.

7. In an internal combustion engine having an intake conduit and an exhaust passage, said intake including a by-pass having a portion heated by said exhaust, a normally closed valve controlling the flow through said by-pass, means responsive to suction for moving said valve to open position, and thermal responsive valve means controlling said intake intermediate the by-pass connection.

8. In an internal combustion engine having an intake conduit and an exhaust passage, said intake including a by-pass having a portion heated by said conduit, a normally closed valve controlling the flow through said by-pass, means responsive to suction for moving said valve to

ward open position, and thermal responsive valve means normally closing said intake intermediate the by-pass connections, said last named valve being capable of opening under excess pressure against the action of said thermal responsive means.

9. In an internal combustion engine, a fuel supply device having means for selectively supplying fuel mixture in accordance with the requirements for maximum economy and a different mixture in accordance with requirements for maximum anti-detonating effect, heating means for said fuel mixture, and means controlled by engine conditions for reducing the effect of said heating means on the fuel mixture when the device is operated to supply the anti-detonating mixture.

10. In an internal combustion engine, a fuel supply device having means for selectively supplying fuel mixture in accordance with the requirements for maximum economy and a different mixture in accordance with requirements for maximum anti-detonating effect, means for heating the mixture supplied by said device, and pressure responsive means for reducing the heating effect of said heating means when the device is operated to supply the anti-detonating mixture.

11. In a fuel supply device for internal combustion engines, means forming a mixture conduit, a fuel supply means discharging into said mixing conduit, valve means for controlling the volume of fuel mixture supplied through said conduit, means for controlling the richness of the mixture in accordance with the requirement for maximum economy during part throttle operation, means for enriching the fuel mixture in accordance with the requirements for maximum power when the valve is moved to nearly wide open position, means for further enriching the mixture in accordance with the requirements for maximum anti-detonating effect when the valve is moved to fully open position, valve means for restricting and normally maintaining a predetermined suction in the discharge outlet whereby the volume of mixture is restricted under low speed conditions, and throttle actuated control means for positively opening said valve means.

12. In a fuel supply device for internal combustion engines, means forming a mixing conduit, a fuel supply means discharging into said mixing conduit, valve means for controlling the volume of fuel mixture supplied through said conduit, means for controlling the richness of the mixture in accordance with the requirement for maximum economy during part throttle operation, means for enriching the fuel mixture in accordance with the requirements for maximum power when the valve is moved to nearly wide open position, means for adding anti-detonant fluid from a separate source to the mixture in accordance with the requirements for maximum anti-detonating effect when the valve is moved to wide open position, valve means for restricting and normally maintaining a predetermined suction in the discharge outlet whereby the volume of mixture is restricted under low speed conditions, throttle operated control means for positively opening said valve means, and means for causing the anti-detonating mixture to be supplied when said restriction is substantially eliminated.

13. In an internal combustion engine, a mixture conduit, a source of fuel supply delivering 75

fuel into said conduit, valve means for controlling said source of supply, a throttle valve, means connecting said throttle and said fuel supply valve whereby movement of said throttle valve to partly and nearly wide open positions will resiliently urge said supply valve to positions, respectively, for economy and maximum power operation, additional means for moving said fuel supply valve to a position for enriching the mixture in accordance with the requirement for maximum cooling and anti-detonating effects when said throttle valve is moved to wide open position, an anti-detonant supply system leading to the conduit, and means effective to open the system when suction in the conduit falls below a predetermined value.

14. A fuel supply device for internal combustion engines, means forming an intake conduit, a fuel supply source, valve means controlling the fuel supply to said conduit, a throttle valve in said conduit posterior to said throttle valve, a source of anti-detonating fuel, and means for supplying the anti-detonating fuel to said conduit when pressure in the conduit is above a predetermined value.

15. A fuel supply device for internal combustion engines, means forming a mixing conduit, a fuel supply source, valve means controlling the fuel supply to said conduit, a throttle valve in said conduit, a volume control valve in said conduit posterior to said throttle valve responsive to suction, and means for mechanically opening said volume control means upon movement of said throttle to wide open position.

16. A fuel supply device for internal combustion engines, means forming a mixing conduit, a fuel supply source, valve means controlling the fuel supply to said conduit, a throttle valve in said conduit, a volume control valve in said conduit posterior to said throttle valve opening in response to suction posterior thereof, a source of anti-detonating fuel, and means for supplying anti-detonating fuel to said conduit and for mechanically opening said volume control means upon movement of said throttle valve to wide open position.

17. The method of supplying fuel to an engine comprising mixing fuel and air in different ratios as required during a power development range with maximum economy, automatically regulating the volume of mixture flow to the engine in accordance with suction developed by the engine, enriching the mixture beyond that of the economy power range for maximum power development, and positively providing a full volume flow of mixture to the engine during the period of enrichment for maximum power development beyond that of the economical power range.

18. In an engine, a carburetion system having a throttle valve and a liquid fuel metering device interconnected for synchronized operation, a fuel mixture delivery conduit for the system, said metering device and throttle valve being associated to vary the air and fuel ratios to provide maximum economy in a power range, a valve in the delivery conduit for controlling the volume of mixture flow, and a connection between the throttle valve and the volume valve whereby full opening of the throttle valve will mechanically open the volume valve.

19. In an engine, a carburetion system having a throttle valve and a liquid fuel valve metering device actuated by the throttle valve, a conduit for delivering the fuel mixture, a volume regulat-

ing valve posterior of the throttle valve, a system for adding anti-detonant fluid to the carbureted mixture, means responsive to engine developed suction posterior of the throttle valve for controlling delivery from the anti-detonant system, and mechanical means for opening the volume valve when anti-detonant is added to the carbureted mixture.

20. In an engine, a carburetion system having a throttle valve and a liquid fuel valve metering device actuated by the throttle valve, a conduit for delivering the fuel mixture from the carburetion system, a suction responsive volume regulating valve in the conduit posterior of the throttle valve, a system for adding anti-detonant fluid to the carbureted mixture, means responsive to engine developed suction posterior to said volume regulating valve for controlling the delivery of fluid from the anti-detonant system whereby the fluid will be delivered when suction development is below a predetermined value, and mechanical means connecting the throttle valve with the volume valve whereby full opening of the throttle valve will mechanically open the volume valve.

21. In the operation of an engine wherein fuel mixture is drawn into the cylinders by piston created suction, the method of controlling the fuel mixture and flow thereof comprising varying the ratio of fuel and air in the power range to obtain maximum economy, controlling the volume flow of the mixture in the economy power range in accordance with suction, enriching the mixture above maximum in the economy power range when the throttle valve is wide open and the engine is in the lower speed range to prevent detonation, and over-ruling suction control of volume flow to provide maximum volume flow while the fuel mixture is being enriched to prevent detonation.

22. In the operation of an engine wherein fuel mixture is drawn into the cylinders by piston created suction, the method of controlling the fuel ratio and flow comprising varying the fuel and air ratio in the power range to provide maximum economy, controlling the volume of mixture flowing to the engine in the economical range in accordance with suction values, adding anti-detonant fluid to the mixture when suction is less than a predetermined value and engine detonation conditions would exist, and increasing the volume flow of the mixture while adding anti-detonant fluid thereto by over-ruling the suction control thereof.

23. In an engine, a fuel feeding conduit, a carburetor connected with the conduit, a throttle valve in the conduit, a suction actuated valve controlling the volume of flow in the conduit posterior of the throttle valve, a connection between the throttle valve and the carburetor for controlling liquid fuel delivery in accordance with throttle valve opening, and a lost-motion connection between the throttle valve and the volume valve whereby the volume valve is mechanically fully opened when the throttle valve is fully opened.

24. In an engine, a fuel feeding conduit, a carburetor connected with the conduit, a throttle valve in the conduit, a suction operated volume control valve in the conduit posterior of the throttle valve, an auxiliary fuel feeding system, means responsive to suction in the conduit posterior of the volume valve for controlling fuel delivery from the auxiliary system, and means actuated by said suction responsive means for mechanically opening said volume valve when suction effecting opening of the volume valve is below a predetermined value.

25. In an internal combustion engine, means forming a mixing conduit for fuel and air, a throttle valve for said conduit, a fuel supply means for supplying a controlled amount of fuel with maximum economy to the conduit during part throttle valve opening, means for increasing the amount of fuel supplied to the conduit beyond that for maximum economy to provide maximum power when the throttle valve is moved to substantially fully open position, means operative only at low engine speeds for further enriching the fuel supplied to the conduit beyond that for maximum power in accordance with the requirements for maximum anti-detonating effect when the throttle valve is in substantially fully open position and engine speed is below a predetermined value, and means for discontinuing said further enrichment for anti-detonating effect while the throttle valve is held substantially fully open and engine speed increases beyond the predetermined value.

26. In an internal combustion engine, means forming a conduit in which fuel and air are mixed, a throttle valve in said conduit, a system for supplying a controlled economical amount of fuel to the conduit when the throttle valve is partly open, and an increased amount of fuel when the throttle valve is farther open beyond the maximum of economy to provide optimum maximum power development, and means under control of vacuum in the conduit for further increasing the fuel supplied to the conduit beyond that for optimum maximum power development while the throttle valve is open beyond maximum economy position and engine speed is below a predetermined value.
